(57) **CLAIM**

The ornamental design for the configurable bin, as shown and described.

DESCRIPTION

FIG. 1 is a top front right perspective view of the configurable bin showing my new design;

FIG. 2 is a left side view thereof, the right side view being a mirror image of the left side view;

FIG. 3 is a front elevation view thereof;

FIG. 4 is a back elevation view thereof;

FIG. 5 is a top plan view thereof, the bottom plan view being a mirror image of the top plan view; and,

FIG. 6 is a top front right view thereof, wherein the broken line showing of an additional bin is for illustrative purposes only.
